FIG. 9.

INVENTOR

Vernie J. Snyder

BY *R. W. DODD, Jr.*

ATTORNEY

UNITED STATES PATENT OFFICE

VERNIE J. SNYDER, OF ALBANY, NEW YORK, ASSIGNOR OF ONE-HALF TO EDMUND C. DEARSTYNE, OF ALBANY, NEW YORK

GRATE

Application filed August 8, 1928. Serial No. 298,326.

My invention relates to grates for furnaces and the like and particularly to a device of this character comprising a minimum number of standardized parts which may be assembled to form a grate of substantially any desired size.

The objects of my invention are to provide a grate of extremely simple character which may be readily adjusted to fit any furnace; which may be readily assembled and taken apart without the use of tools; and in which the separate elements thereof will, when assembled in place in the furnace, act to maintain the whole in assembled relation.

With these objects in view my invention includes the novel elements and combinations and arrangements of elements described below and illustrated in the accompanying drawings in which—

Fig. 1 is an elevation view of a rocker or grate-supporting bar;

Fig. 2 is a section of Fig. 1 in the plane 2—2;

Fig. 3 is a section of Fig. 1 in the plane 3—3;

Fig. 4 is a plan view of Fig. 1;

Fig. 5 is a plan view of one transverse section of my grate showing the rocker or supporting bar with the grate elements assembled thereon;

Fig. 6 is an enlarged section of Fig. 5 in the plane 6—6 showing how the two portions of the rocker bar interfit and how they are held in interfitting relation by the grate elements saddled thereon.

Fig. 7 is similar to Fig. 6 and is a section in the plane 7—7 of Fig. 5;

Fig. 8 is an end view of one of the grate elements; and

Fig. 9 is a side view showing five grate sections journaled in the side support, and the means for shaking the grate.

Referring to the drawings, my grate comprises a rocker bar represented generally by the numeral, 1, and which comprises the separate portions, 2 and 3. Portion 2, comprises the generally rectangular bar, 4, cast integral with the end element, 5, which carries the rocker shaft, 6. Portion 2, is pro-

vided with a projection, 7, on the side thereof which is adapted to interfit with a recess, 8, provided in the side of the portion, 3. The portion, 3, comprises the generally rectangular bar, 9, cast integral with the end element, 10, which latter is quite similar to element, 5, except that it is provided with a comparatively long depending portion, 11, to which a shaking bar, 12, (see Fig. 9) may be attached. When the portions, 2 and 3, are placed together in interfitting relation, as shown in Figs. 4 and 6, the rocker shaft, 6, on end element, 5, is aligned with rocker shaft, 13, on end element, 10.

The bar, 1, serves as a support for the separate grate elements, 14, which are simply saddled thereover. These elements are preferably cast in the form shown in Figs. 5, 6, 7 and 8. The fuel supporting surfaces are preferably but not necessarily arcuate and may be provided on the sides with teeth or serrations, 15, as illustrated. These grate elements have comparatively heavy depending portions, 16, which are designed to embrace the sides of bar, 1. Where the portions, 2 and 3, of the bar, 1, overlap, the depending portions, 16, are so spaced that the grate element will just slip over the bar and hold the interfitting portions, 2 and 3, in closely assembled relation as shown in Fig. 6. Over those portions of the bar, 1, which are, so to speak, of single thickness, one of the portions, 17, depending from the grate elements is slightly increased in thickness, as shown in Fig. 7, so that it is adapted to closely embrace the side, for example, of portion, 2, of the bar, 1. Although no means for locking the grate elements on the rocker bar is necessary, the depending portions, 16, may be provided with an opening, 18, through which a cotter pin, 19, may be inserted as shown in Fig. 6. The transverse thickness, 20, (see Fig. 8) of the portions, 16, may vary, depending upon the spacing desired and which will be best adapted for the particular sizes of fuel to be burned. Likewise, the length of these elements may vary and preferably should be such that the center of gravity of the grate sections is substantially below the axis of the rocker shafts, 6 and 13, 100

so that the normal position of the depending portions, 16, will be vertical.

In assembling my grate in the furnace, the rocker shafts are separately inserted in the side supports, 21, and the portions, 2 and 3, are then interfitted. When in this position, a single grate element slipped over the central portion of the rocker bar, 1, where the portions, 2 and 3, overlap, will temporarily hold the rocker bar in place. The other grate elements may then be saddled over the rocker bar, and when the entire bar is filled the shafts, 6 and 13, will be held in the side supports and cannot be withdrawn without removing one or more of the grate elements so that the bar, 1, is shortened. When it is desired to remove a grate section from the furnace, all that is necessary is to remove one or two of the grate elements at either end of the rocker bar so that the bar may be slightly shortened and one shaft thus withdrawn from its bearing in the side supports. Should any one of the grate elements become burned or otherwise damaged, it is only necessary to lift it off the rocker bar and replace it with a new one.

From the foregoing it will be apparent that my grate sections may be adjusted to fit any side support spacing whatever by simply pulling the end elements, 5 and 10, out to the proper distance, inserting the shafts, 6 and 13, in the side supports and locking the section in place by assembling the grate elements on the rocker bar.

While I have described my invention somewhat in detail for the purpose of clearness it is to be understood that the words which I have used are words of description rather than of limitation and that changes within the purview of the appended claims may be made without departing from the true scope and spirit of my invention.

What I claim is—

1. In a grate, the combination with a rocker bar comprising two slidably interfitting portions adapting said bar to be lengthened or shortened, of a plurality of grate elements saddled thereon; some of said elements closely engaging both said portions and preventing lateral separation thereof.

2. In a grate, the combination with a rocker bar comprising two slidably interfitting portions adapting said bar to be lengthened or shortened, of a plurality of grate elements saddled thereon; some of said elements closely engaging one of said portions and preventing the shortening of said bar while said portions are interfitted.

3. In a grate, the combination with a rocker bar comprising two slidably interfitting portions adapting said bar to be lengthened or shortened, of a plurality of grate elements saddled thereon; some of said elements closely engaging both of said portions and preventing lateral separation thereof, and

other of said elements engaging one only of said portions and preventing the shortening of said bar.

4. In a grate, the combination with side supports, of a transverse rocker bar journaled therein and comprising two sections relatively movable longitudinally, a plurality of separate grate elements saddled thereover and coacting directly therewith, said grate elements locking said rocker bar in assembled, journaled position, and said grate elements being located adjacent to each other and forming a series substantially co-extensive with the width of the grate.

5. In a grate, the combination with a rocker bar comprising two elements provided with complementary interfitting portions and relatively movable longitudinally, of a plurality of separate grate elements saddled thereon and securing said rocker bar elements in interfitted relation, and said grate elements being located adjacent to each other and forming a series substantially co-extensive with the width of the grate.

6. In a grate, the combination with an extensible rocker bar comprising separate elements provided on the sides thereof with complementary interfitting portions, of a plurality of separate elements forming the surface of the grate, and saddled over and closely embracing said rocker bar throughout its extent to secure the whole in assembled relation.
